(57) **CLAIM**

The ornamental design for a surface mounted modular exercise device, as shown and described herein.

DESCRIPTION

FIG. 1 is a top, front, left side perspective view of an exercise device according to an embodiment of the present invention;

FIG. 2 is an enlarged detail view of a portion of the exercise device shown in FIG. 1;

FIG. 3 is an enlarged detail view of another portion of the exercise device shown in FIG. 1;

FIG. 4 is a front elevation view of the exercise device shown in FIG. 1;

FIG. 5 is a right side elevation view of the exercise device shown in FIG. 1;

FIG. 6 is a left side elevation view of the exercise device shown in FIG. 1;

FIG. 7 is a rear elevation view of the exercise device shown in FIG. 1;

FIG. 8 is a top plan view of the exercise device shown in FIG. 1, shown at an enlarged scale; and,

FIG. 9 is a bottom plan view of the exercise device shown in FIG. 10, shown at an enlarged scale. The broken lines in FIG. 1 depict environmental subject matter only and form no part of the claimed design.
